UNITED STATES PATENT OFFICE.

FRANK STEINER, OF CHICAGO, ILLINOIS, ASSIGNEE TO STANDARD ELSMERE GRANITE CO., A CORPORATION OF ILLINOIS.

FITTING.

Application filed March 30, 1922. Serial No. 547,947.

To all whom it may concern:

Be it known that I, FRANK STEINER, a citizen of the United States, residing at Chicago, in the county of Cook and State of Illinois, have invented a certain new and useful Improvement in a Fitting, of which the following is a full, clear, concise, and exact description, reference being had to the accompanying drawings, forming a part of this specification.

My invention relates to the metal portion of laundry tubs formed chiefly of synthetic stone.

One object of the invention is to simplify the construction and assembly of the metal facing portion along the upper edge of such a tub, particularly at the corners.

Another object is to provide a joint which will be more easily kept clean in service.

Other objects and advantages of the invention will become apparent as the description proceeds.

In the accompanying drawings, Figure 1 is a perspective view of a laundry tub, illustrating the application thereto of fittings according to my invention. Fig. 2 is a bottom plan view of the ends of the fittings adjacent the corner slightly removed from assembled position. Figure 3 is a perspective view of the assembled fittings. Figs. 4 and 5 are end views of the front and side fittings respectively.

Fig. 6 is a side view of the end of the side fitting.

In the embodiment of my invention selected for illustration, the tub 10 carries an edge or facing 12 of metal along one edge and a similar facing 14 along the end. The outer depending portion of facing 14 extends downwardly at 16 to provide bearing surface for engagement with suitable wringer clamps, or similar devices. Both facings are provided along their longitudinal edges with narrow inturned flanges 18, which enter the material of which the tub 10 is formed to fasten the parts securely in place.

According to my invention the top 20 of the front facing is cut off at an angle of 45° as at 22, and the front 24 extends beyond the same, being bent in at right angles to form a tab 26, the edges of which are tapered as clearly shown in Fig. 4.

The top 28 of the end facing is left with squared ends. It will be seen that the angle

between the top and the side of the end facing can be thrust over the tab 26, and that the inclined edge of the tab will wedge the end facing tightly up under the top 20 of the front facing. The flange 18 at the inner edge of the top 20 is preferably extended beyond the top as at 30 to underlie the edge of top piece 28 and hold the inner edge of top 20 securely in place. This makes it possible to jam tongue 26 tightly in place without tipping up the surface 20. In the assembled position shown in Fig. 3, the parts are embedded in the material of the tub when it is formed.

Side piece 16 is permitted to have a notch 32 in its inclined edge. When side piece 16 is not to extend down far enough to receive fastening screws for a wringer the same punch may be used on stock only wide enough to come to the lower edge of notch 32, and the notch will facilitate bending in an edge 18 from the narrower strip.

Without further elaboration, the foregoing will so fully explain the gist of my invention, that others may, by applying current knowledge, readily adapt the same for use under various conditions of service, without eliminating certain features which may properly be said to constitute the essential items of novelty, which items are intended to be defined and secured to me by the following claims.

I claim—

1. In combination with a structural body wall, metal facings for said wall along its edge, the ends of said facings overlapping each other, the end edge of the upper facing being cut at an angle running across the upper edge of said wall.

2. In combination with a structural body wall having an angle therein, facings for said wall, the ends of said facings overlapping each other at the angle of said wall, the overlying end being cut at an angle so that its edge crosses the surface defining the edge of said wall diagonally.

3. In combination with a structural body wall, facings having overlapping ends, the end lapping over carrying a projection underlying the end lapping under to hold the parts in assembled position, said projection having an inclined edge arranged to wedge the underlying end against the overlying end.

4. In combination with a structural body

wall, facings having overlapping ends, the end lapping over carrying a projection underlying the end lapping under to hold the parts in assembled position, said projection having an inclined edge arranged to wedge the underlying end against the overlying end, said overlapping end having also a lug spaced from said projection to underlie the underlying end and prevent tipping of the parts by the wedging action of said projection.

5. In combination with a structural body wall, facings having overlapping ends, the end lapping over carrying a projection underlying the end lapping under to hold the parts in assembled position, said projection having an inclined edge arranged to wedge the underlying end against the overlying end, said ends having additional interlocking means spaced from said projection to prevent tipping by the wedging action.

6. In combination with a structural body wall having an angle therein, facings having ends overlapping at said angle, the edge 25 of the overlapping end lying in a line oblique to the planes of the wall portions on both sides of said angle.

7. In combination with a structural body wall, facings having overlapping ends, and 30 interlocking means at both sides of said overlapping ends to draw the parts together.

8. In combination with a structural body wall having an angle, facings for said wall having ends overlapping at the angle, and 35 interlocking means at both sides of said overlapping ends to draw the parts together, the interlocking means at the outside of the angle having a wedging action.

9. In combination with a structural body wall, facings having overlapping ends, and 40 interlocking means at both sides of said overlapping ends to draw the parts together, one of said interlocking means having a wedging action.

10. In combination with a structural body wall, facings having overlapping ends, and 45 interlocking means having a wedging action for holding said ends in contact.

11. In combination with a structural body wall having an angle, facings covering the 50 edges of the wall portions forming said angle, said facings having ends overlapping at the angle, a wedging interlock between said facing ends on the outer side of the wall, and an interlock between said ends on the 55 inner side of the wall.

12. In combination with a structural body wall having an angle, facings covering the edges of the wall portions forming said angle, said facings having ends overlapping at 60 the angle, and interlocks between said ends on opposite sides of the wall at the angle, the edge of the overlying end extending diagonally across the wall in a substantially 65 straight line between said interlocks.

13. In combination with a structural body wall having an angle, fittings having ends overlapping at said angle, the edge of the overlying end running across the wall at an 70 angle to the planes of both walls and being held in firm mechanical contact with the underlying end but not integrally united thereto.

In witness whereof, I hereunto subscribe my name this 28 day of March, 1922.

FRANK STEINER.
